UNITED STATES PATENT OFFICE.

FRANK E. TEN EYCK, OF AUBURN, NEW YORK.

AIR-PUMP.

No. 858,039.

Specification of Letters Patent.

Patented June 25, 1907.

Application filed August 30, 1902. Serial No. 121,617.

To all whom it may concern:

Be it known that I, FRANK E. TEN EYCK, of Auburn, in the county of Cayuga, in the State of New York, have invented new and useful Improvements in Air-Pumps, of which the following, taken in connection with the accompanying drawings, is a full, clear, and exact description.

This invention relates to improvements in air pumps, being particularly applicable for inflating heavy pneumatic tires as used for automobile wheels.

One of the objects of this invention is to produce a hand operated air pump in which the leverage increases as the air is compressed, or in other words, to connect the operating lever in such manner that its fulcrum moves gradually from a position remote from the axis of the piston rod to a position in alinement with or slightly beyond said axis when the piston is in its compressed position, thereby locking the piston against reaction by the elasticity of the compressed air.

Another object is to relieve the cylinder from any strain by connecting the fulcrum of the operating lever to a suitable base upon which the cylinder is mounted.

A further object is to provide the outlet passage of the cylinder with a suitable check valve to prevent the re-entrance of the compressed air from the pneumatic tire back into the cylinder.

To this end the invention consists in the combination, construction and arrangement of the parts of an air pump as hereinafter fully described and pointed out in the claims.

Referring to the drawings—Figure 1 is an elevation of my improved air pump, the operating lever and link and the piston connected thereto being shown in their elevated positions in full lines and in their intermediate and extreme downward position by dotted lines. Fig. 2 is a front elevation of the device seen in Fig. 1, the operating levers and the parts connected thereto being shown in their lowermost position. Fig. 3 is a transverse vertical sectional view through the device, as seen in Fig. 2. Fig. 4 is a horizontal sectional view taken on line —4—4—, Fig. 1. Fig. 5 is a vertical sectional view of the detached bushing or nipple in which the outlet passage and valve are located.

Similar reference characters indicate corresponding parts in all the views.

In carrying out the objects of my invention, I preferably employ an upright cylinder

—1— having lower and upper end heads —2— and —3—, the lower head —2— being of greater area than the head —3— and forms a suitable supporting base upon which the various parts of my invention are mounted either directly or indirectly.

The cylinder —1— receives a suitable piston —5— having a rod —6— projecting upwardly therefrom through an opening in the head —3— and is guided in a bushing —7— removably secured in the opening in the head —3—, said opening and bushing being usually threaded.

The lower end of the cylinder —1— is preferably threaded and engages a threaded aperture —8— in the upper end of the base —2—. This base is formed with a lateral chamber 10— communicating with the interior of the cylinder —1— at a point beneath the piston, one of the walls of the lateral chamber —10— being provided with an outlet opening in which is removably secured a nipple —11—. This nipple forms one of the features of my invention, being provided with a lengthwise passage —12— and a valve seat —13— for receiving a valve —14— which operates to close the passage —12— against the re-entrance of the compressed air from the inflated tire back into the cylinder, it being understood that the passage —12— communicates with the chamber —10— and that the nipple —11— is provided with a projecting end having engaging shoulders for receiving one end of a pneumatic tube not shown, which tube, however, is usually employed in connection with an air pump for conducting the compressed air to the tire to be inflated.

The base —2— is usually formed of cast metal and is provided with an annular foot —14'— and upwardly projecting ears or lugs —15— rising from the flange —14'— and preferably cast integral with the base, the flange —14'— being provided with a series of apertures —16— for receiving fastening members, as bolts not illustrated, but which are employed to secure the pump to some particular fixed body if desired.

Pivotedly connected to the lugs —15— by a suitable pivotal bolt —17— is a link —20— extending upwardly from the pivot —17— beyond the upper end of the cylinder head —3— and is provided with a lateral off set —21— which overhangs the upper end of the cylinder when the piston is in its depressed position.

The upper end of the piston rod —6— is provided with a bifurcated head —22— to which is pivoted by a suitable bolt —23— a hand operated lever —24—, said lever —24— being fulcrumed to the upper end of the link —20—, or rather to the free end of the offset portion —21— by a pivotal bolt —25— and the free end of this lever is provided with a recess —26— in its end face in which is seated a handle —27— projecting laterally in opposite directions from the adjacent portion of the lever and is held in position by a clamping bolt —28— engaged with the threaded socket —28'— in the end of the lever.

15 The arm of the lever provided with a handle —27— is considerably longer than the distance between the pivotal bolts —23— and —25— so as to afford as great leverage as possible in operating the piston and in order to effect the full movement of the piston and to obtain the utmost compressive force in the easiest and most efficient manner this lever is of such construction that the fulcrum gradually moves toward the axis of the piston rod

25 during the descent of the piston so that the leverage and therefore the power exerted upon the piston is gradually increased as the resistance of the air increases and at the same time the longer arm of the lever assumes

30 a position below the horizontal level of the pivotal bolts —23— and —25— and permits the operator to bring his whole weight and strength to bear upon the further downward movement of the lever, and therefore upon

35 the piston. When the piston approaches the limit of its downward movement as actuated by the lever —20— the fulcrum —25— moves slightly beyond the axis of the piston rod, and therefore automatically locks the piston from

40 reactionary movement due to the elasticity of the compressed air. In order to accomplish these results the lever —24— is provided with lateral offsets —29— and —30— at opposite sides of the pivotal bolt —23—

45 somewhat in the form of a letter **S**. The particular forms of link —20— and lever —24— are important features in my invention for the reason that by constructing said parts 20 and 24 with the offsets —21— and —29— I am enabled to diminish materially the distance between the pivotal connections —23— and —25— as compared with the distance from the bolt 23 to the handle —27—, thereby obtaining a far greater power than

55 would be possible with a straight link. The lever is movable through an arc of substantially half a circle or nearly 180° so as to give the greatest possible movement to the piston in a single stroke of the lever and the distance

60 between the fulcrum and pivotal connection of the lever with the piston rod is therefore

substantially equal to half the stroke of the piston, while the long arm of the lever may be, and is—in this instance, fully as long as the cylinder.

65 A feature of advantage of disposing the arm —30— of the lever at an angle with its intermediate portion, is that I am enabled to move the lever closely to the base of the cylinder and more directly under the weight of 70 the operator at the period of greater resistance to compression.

Another important advantage of the particular connection of the link —20— with the base —2— is that the cylinder proper is relieved from any torsional or lateral strain during the act of compressing the same, such as would occur if the link were connected directly to the cylinder or to the upper head.

75 It is apparent from the foregoing description that during the operation of compressing the air in the cylinder in advance of the piston, the action of the lever is from a minimum to a maximum leverage, that is, the fulcrum moves from its extreme remote position 80 from the axis of the piston rod in its starting position to a position directly over and slightly beyond said axis at which time the piston is moved to the full limit of its downward stroke.

90 The main cylinder —1— is preferably formed of tubing, and the heads —2— and —3— are preferably formed of cast metal, these parts being threaded and screwed to each other and therefore affords a simple and economical means of assembling said parts.

95 The operation of my invention will now be readily understood upon reference to the foregoing description and the accompanying drawing.

100 Having thus described my invention what I claim and desire, to secure by Letters Patent is—

A device of the character described comprising a cylinder, a base, said base extending substantially half way across the bottom of said cylinder, and having an enlarged portion forming a chamber wholly within said base, a piston operating in said chamber, a link pivoted to said base, and a handle pivoted to one extremity of said link at its own extremity and pivoted to said piston at a point between its two extremities, said handle and said link so formed as to conform to the upper surface of said cylinder, substantially as described.

115 In witness whereof I have hereunto set my hand this 26th day of August, 1902.

FRANK E. TEN EYCK.
